UNITED STATES PATENT OFFICE.

THEODORE YATES, OF MILWAUKEE, WISCONSIN.

CARTRIDGE.

SPECIFICATION forming part of Letters Patent No. 308,941, dated December 9, 1884.

Application filed March 8, 1884. (No model.)

To all whom it may concern:

Be it known that I, THEODORE YATES, of Milwaukee, in the county of Milwaukee and State of Wisconsin, have invented certain Improvements in Cartridges for Cannon, of which the following is a specification.

My invention relates to cartridge-cases for ordnance, the novel features of which are hereinafter fully set forth.

10 Figure 1 is a longitudinal central section, showing the parts ready for charging the gun, and Fig. 2 is a similar view, showing the parts as they appear after the gun has been fired.

The object of my present invention is to provide a cartridge-case adapted for use in breech-loading cannon, it being more especially designed for use in connection with the gun on which a patent was granted to me under date of June 28, 1881, No. 243,421, though it may 20 be used in connection with other styles of guns also.

The special objects of the invention are to so construct the case which is to contain the charge of powder that it can be filled at the 25 arsenal, or any suitable place, and keep its form while being transported, protect the powder from the effects of wet and moisture, and provide it with a head or cap at its front end which shall serve as a gas-check in rear 30 of the projectile when the charge is exploded.

It further consists in so constructing the case and its head or breech closer, that they can be handled separately, and yet be united by the explosion in such manner that the powder-case may be withdrawn by the withdrawal 35 of the head, and so as to be fired by the explosion of a small ball-cartridge seated in an aperture in the head, and also to protect the walls of the gun by the interposition of an 40 air-cushion between the case and the walls of the chamber of the gun. To accomplish these results I provide a breech-closer or plug, A, of a proper size to close the rear end of the chamber of the gun, its front end being made 45 concave, as shown clearly in Fig. 1, its front walls being extended, as shown, and made sufficiently thin at their front edge to allow of 50 expansion, and thus form a tight joint on the well-known principle of the ordinary metallic cartridge, though, as will be hereinafter seen, the powder-case will aid to form a tight joint

at the time of explosion. This breech-closer A, which for convenience I term the "cartridge-head," has a screw-thread, b, or any equivalent recesses or projections formed on 55 its interior near or at its front end, as shown in Fig. 1, the object of which will be herein-after explained. It is also provided with a projecting rim or flange, d, to fit a corresponding recess in the rear end of the gun, to prevent it from being shoved too far in, and aid in its extraction. At its center it is provided with a hole, h, of proper size to receive a small pistol-cartridge for firing the charge, as shown in Fig. 1.

The powder-case B, I make of tin, copper, or any suitable sheet metal of the size required for the charge. The rear end of this case B, I make spherical, or of a form to fit the concavity in the front end of the head A, and 70 of such a size that it will easily fit therein, and I provide the body of the case B with a series of corrugations, l, more or less in number, for the purpose of stiffening it and enabling it to retain its form or shape while being handled and transported, and which also leave air-spaces between it and the walls of the gun, thereby forming an air-cushion, which serves to protect the gun from the sudden shock caused by the explosion of the charge. 75

While I have shown the corrugations l as being annular, or passing around the case at right angles to its length, it is obvious that they may be arranged spirally or diagonally 85 in either or both directions, or that they may be formed both circumferentially and longitudinally, and that they may be made to occupy any proportion of the surface desired. At its front end this case B is closed with a cap, C, which is soldered to the body, as represented in Fig. 1. It is provided with a central opening for inserting the powder, which opening is closed by a screw-cap, e, as represented in Fig. 1, the cap C being made dishing or concave externally, so that when 90 the case is set on end the cap e will not be touched. By this means the cap e is protected when the case is being handled, transported, or stored. At its rear end a small cone, f, is secured internally, so that it may be flattened 95 down by the pressure of the gas when the charge is exploded, and thus close the open-

ing formed by the bullet of the cartridge *c*, which will puncture the rear end of the case at its center when fired.

Within the case *B*, at its front end, I arrange a disk, *D*, of felt or similar material to serve as a wad, it having a hole where the powder is inserted, as shown in Fig. 1. It may be secured by any suitably-adhesive material to the cap *C*, so that the gas will not get between them.

The charge will usually be composed of grains of powder too large to enter the cone *f*, so that when the charge is exploded there will be little or no pressure by the formation 15 of gas within the cone, while the pressure upon its exterior will be sufficient to force the walls of the cone inward and cause it to close the perforation made by the penetration of the pistol-ball, which of course will be very 20 small, only sufficient to perforate the rear end of case *B* to admit the flash from cartridge *c* to ignite the powder. This cone *f* may be made of any desired size, and, if desired, it may be 25 prolonged in the form of a tube, so as to conduct the flame to the center, or even to the front end of the charge, and thus ignite it at either of those points first. If found desirable in practice, it may be so enlarged as to 30 form an air-chamber, and thus be made to furnish an additional supply of oxygen to render the combustion of the powder more perfect. Various modifications may be made in 35 this particular without at all affecting the main features of the invention. These cases *B*, being fire and water proof, may be filled at the powder-factory or any powder-depot, and be transported and stored for any length of time wherever wanted, the cases *B* thus in effect taking the place of and dispensing with 40 the ordinary package used for transporting the powder. While of course these cartridges or cases may be used with any style of projectile, it is my intention to use a projectile which does not have the usual expanding 45 sabot, and hence the provision for making the cap *C* of the case *B* so that it will act as a gas-check in rear of the projectile.

The operation of my device is as follows: The projectile having been first placed in the 50 gun the case *B*, properly charged, has its rear end inserted in the head *A*, and the cartridge is then shoved into the chamber of the gun. The igniting-cartridge *c* is inserted in the hole *h* and the breech of the gun being closed the 55 charge is fired by igniting the small cartridge *c*, which will ordinarily be done by a firing-pin located in the breech closing or locking devices, according to the style of gun used. When the small cartridge *c* is fired, its 60 ball will be driven forward, and will puncture or perforate the rear end of the case *B* when the flame from the cartridge *c* will ignite the powder in case *B*, thus exploding the charge. This will separate the cap *c* from the 65 body of the case when the gas, acting against its rear face, will force its flange out all around against the sides of the chamber and thus form

a gas-tight joint in rear of the projectile, which will thus receive the whole force of the powder; and inasmuch as the projectile is designed to 70 fit the bore of the gun and not to have any expanding sabot to act as a wedge, thereby tending to burst the gun and creating great friction, the result will be increased velocity of the projectile and consequently greater 75 range and penetration. At the same time the force of the gas within the base *B* will flatten down the cone *f*, thereby closing the perforation made by the small cartridge-ball and will force the thin metal of the case *B* into the 80 screw-threads *b* of the head *A*, whereby the two will be sufficiently united to enable the case *B* to be drawn out with the head *A*, the case *B* after the explosion being in the condition represented in Fig. 2. By detaching it 85 from the head *A* a charged case can be substituted, and the whole will be ready for use as before. It will of course be understood that the head *A* will be kept with the gun and can be used repeatedly. By having two or 90 more of them the case *B* can be applied to one while the other is in the gun, and thus be ready for insertion the moment the exploded case is withdrawn. The metal cases *B* will 95 also protect the chamber of the gun from injury by the heated gases and when withdrawn will leave the chamber clean and free from all débris or accretions of any kind ready for the instant insertion of another charge.

As the breech-closer *A* has its walls at the 100 front made thin, so as to expand and form a gas-check, it will be seen that in case the supply of powder-cases should fail the gun can still be used by supplying powder put up in cloth sacks or bags, as has been customary for muzzle-loading guns, and this not unfrequently may prove of great importance.

While I have shown a screw-thread as the means used for causing the case *B* to adhere to the head *A*, I do not wish to be understood 110 as being limited to that, as it is obvious that other forms of projections or indentations may be used for locking the parts together by the pressure of the gas, care being taken not to make an opening in the walls of the breech-closer *A* through which the gas might escape 115 by rupturing the case *B*.

I am aware that a cartridge has been made for small-arms in which a cap carrying the fulminate and provided with an oblong slot 120 in its wall or side was made to fit over the rear portion of the cylinder which contained the powder.

I am also aware that cartridges for small-arms have been made with a re-enforce permanently secured to the rear end of the shell both internally and externally, and I make no claim to any such devices; but,

Having fully described my invention, what I claim is—

1. A breech-closer for ordnance, consisting of a plug, *A*, adapted to fit in the rear open end of the chamber of the gun, said plug having a concave chamber formed in its front end,

the front end of the walls of said chamber being made thin to enable it to expand and form a gas-check, and having on the inner face of said walls a screw-thread or equivalent indentations or projections, whereby said breech-closer is adapted to be used with or without the metallic powder-case, substantially as herein set forth.

2. A breech-closer, A, substantially such as shown, having a concave chamber formed in its front end, the inner surface of the walls of said chamber being provided with a screw-thread or equivalent projections or indentations, in combination with a separate or detachable powder-case, B, having its rear end adapted to fit into said chamber, said parts being constructed substantially as described, whereby the powder-case is adapted to be filled and transported independently of the breech-closer, and both are adapted for joint use in the gun, as set forth.

3. A metallic powder-case, B, provided with the concave cap C, having an opening for inserting the powder, with a screw-cap or equivalent device for closing the same, and having its opposite end of a shape corresponding to the form of the chamber in the front end of the separate breech-closer, substantially as and for the purposes set forth.

4. A closed cartridge or powder case, B, for 30 cannon, having its body corrugated to enable it to retain its form, as described, and provided with a concave cap, C, at one end, whereby it can be set on end, handled, and transported, and be ready for insertion in the gun without 35 further preparation, as set forth.

5. A metallic powder-case for use in cannon, provided at its front end with metallic cap C, having a flange formed integral with the body of the cap for the purpose of serving as a gas-check in rear of the projectile when the charge is fired, substantially as described.

6. The combination, in a cartridge for ordnance, of the closed metallic powder-case B, 45 a head or breech-closer, A, and a ball-cartridge, c, for puncturing the metallic case and igniting the charge, substantially as set forth.

7. In combination with a metallic powder-case, B, provided at its front end with the 50 flanged cap C, the fibrous disk or wad D, secured to the inner face of said cap, substantially as shown and described.
